MEYER GROSSMAN, OF NEW YORK, N. Y., ASSIGNOR OF ONE-HALF TO ADOLPH M. DEUTSCH, OF NEW YORK, N. Y.

EXTENSION TABLE.

1,415,549.

Specification of Letters Patent. Patented May 9, 1922.

Application filed July 16, 1919. Serial No. 311,136.

To all whom it may concern:

Be it known that I, MEYER GROSSMAN, a citizen of the United States, residing at New York, in the county of Bronx and State of New York, have invented certain new and useful Improvements in Extension Tables, of which the following is a specification.

The invention relates to tables, the tops of which are divided into two main portions 10 that are adapted either to be brought together or to be separated to permit the insertion of one or more auxiliary leaves therebetween.

Primarily, the invention has for its object 15 to provide an extension table in which the additional leaves will be carried under the main portions of the top or cover of the table and can be easily placed into and out of operative position, without interfering in any 20 manner with the other parts of the table structure.

Another object of the invention is to produce an extension table composed of a plurality of sections capable of being parted 25 or held together, and having one or more compartments wherein auxiliary leaves may be stored for eventual use, and meanwhile will admit of the employment of a single central support for the entire table.

30 A further object is the production of a table of the nature set forth, within which the auxiliary leaves, when not in use, shall be actually concealed by the main sections and kept in parallelism thereunder to enable 35 them to be readily withdrawn at such time as they are wanted for use.

Still another object is the provision of 40 means designed to hold the said leaves in a stable manner, each interiorly of its respective compartment, and further to guide the leaves during their retraction therefrom until they are set for use between the said main table sections.

An additional object is to supply the sub- 45 structure of the table and the auxiliary leaves therefor with cooperating supports serving to sustain the latter firmly upon the former, and combining with the said guiding means to maintain the leaves at the 50 required level after they are set in their operative positions.

Other objects and advantages of the invention will in part be obvious and in part be more fully explained in the following de- 55 scription.

The invention consists of the novel parts, improvements, combinations and features of construction herein shown and described.

The accompanying drawings, which are referred to herein and form a part hereof, 60 illustrate one embodiment of the invention, the same serving in connection with the description herein to explain the principles thereof.

Of the drawings: Figure 1 is a top plan 65 view of an extension table constructed in accordance with the main principle of the invention; Figure 2 is a side elevation of the same; Figure 3 is a transverse section, on the line 3-3 of Fig. 1, looking toward the 70 left; Figure 4 is a top plan view, showing the table extended out for its full length, and fitted with a plurality of added leaves; Figure 5 is a longitudinal section on the line 5-5 of Fig. 4, looking up in the direction of 75 the arrows; Figure 6 is a similar section of the extended table, with the central portion thereof devoid of leaves; Figure 7 is a longitudinal section illustrating the manner of removing a leaf from the table; Figure 8 is 80 a top plan view, representing the table extended, with a single leaf occupying the center thereof; Figure 9 is a longitudinal section on the line 9-9 of Fig. 8, as viewed in the direction pointed out by the arrows 85 in the latter-named figure; Figure 10 is a fragmentary view, illustrating a special construction of auxiliary leaf, provided with an apron foldable thereunder; and Figure 11 is a similar view, showing this same form of 90 leaf with its said apron unfolded and lowered to an operative position.

Referring to the drawings in detail, the embodiment of the invention illustrated 95 comprises a pedestal 11, which, as clearly seen in Fig. 2, may constitute a single, central support for the entire table. It is a peculiarity of the present invention that the table can be utilized optionally in contracted form, or half drawn out, or spread to the 100 fullest extent, and yet the constituent parts thereof in all these conditions will be so well poised as to maintain the top surface firm and level throughout, while presenting no obstruction to the feet of the persons sitting 105 therearound, as happens where corner or end supports are employed. This feature of the invention, it will be noted, is disclosed more or less distinctly in all but the detailed views of the annexed drawings.

Upon the said pedestal is rigidly secured a frame of cruciform configuration, including horizontally disposed members 14 and 15, that are crossed at the center and extend 5 cut in both directions diagonally therefrom, each a sufficient distance to provide a firm support for the several slides, guides, and other elements composing the substructure of the table. Among the latter are two 10 guide-rails 16 and 17, which span the crossed members of the frame on opposite sides thereof and may be fastened by any suitable means to the upper faces of the respective members, near their extremities.

15 The table proper, when used in its contracted form, as illustrated in Figs. 1 to 3, consists preferably of two parts of equal dimensions, indicated by the reference numerals 19 and 20. Both parts may be rounded 20 at the corners as shown, or given any other desirable contour, but they are cut straight at their inner edges, so as to meet squarely and effect a smooth joint at the center.

An apron, as 21, is provided for each 25 half of the table, the same consisting of a flange-like element depending from each of the said parts 19 and 20, but reversed in position one relatively to the other. The opposite edges of the pair of aprons thus 30 formed are arranged to abut against one another, directly under the meeting line of the two halves 19 and 20 of the table, and consequently the parts are solidly maintained when brought together, as exemplified in Fig. 2. At the corners, the two 35 aprons 21 are rounded in a similar manner to the said halves.

Underneath the main parts of the table, as represented in the said Fig. 2, are placed 40 auxiliary leaves 23 and 24, either or both of which may be inserted intermediate the said parts, in order to form a desired extension. Ordinarily, two such leaves will be sufficient, and therefore this number only 45 is included in the present embodiment of the invention, although it is not to be considered as restricted in that respect.

When not in use, the said auxiliary leaves are held close under the adjacent inner portions of the table halves 19, 20, with their 50 opposite ends resting in slots, as 26, cut into the upper edges of the aprons 21. The latter, therefore, act as supports for the auxiliary leaves while they remain in their 55 inoperative positions. In this way, the leaves are kept from view by the overlying parts of the table, and besides they offer no impediment whatsoever at any time while the table is being used.

60 The auxiliary leaves further may be provided with aprons 28, 29, suitably fastened to the under side thereof, near their opposite extremities. These aprons are supplementary to the table aprons 21, previously 65 mentioned. As shown in Figs. 1, 2 and 3,

the aprons 28 and 29 are placed on the inside of the aprons 21, and when the table is extended, as in some of the other figures of the drawings, they serve to close the gaps intervening between the parted halves 70 19 and 20, at the opposite sides of the table. This is accomplished by pulling the said leaves out of their respective slots 26, which are left open at their inner ends for the purpose, and by locating the drawn-out 75 leaves, or either one of them, midway between the said parted halves, in the manner hereinafter described. A special mode of construction for the aprons of the auxiliary leaves will also be subsequently explained. 80

Slidebars, as 31 and 32, are attached to the under side of each one of the main parts 19 and 20 of the table, so as properly to support the same upon the diagonally arranged members 14 and 15 of the cruciform frame, and further to enable the said parts 19, 20 to be pushed toward or pulled away from each other in effecting the desired table adjustment. A pair of such bars, it will be seen, is provided for each half 90 of the table. Preferably, these bars are located on opposite sides of the rails 16 and 17, before referred to, which they respectively engage, for instance, by means of dovetailed grooves and tenons, as indicated at 33 and 34, in Fig. 3.

To the under side also of each auxiliary leaf is secured a pair of runners, as 37, adapted to bear upon or else extending alongside of the cruciform frame aforesaid, 100 when either leaf occupies its lowermost position, under the corresponding superimposed part of the table, 19 or 20, as the case may be. This position is indicated in Figs. 3 and 6, as also at the right-hand side of 105 Fig. 7. The runners 37, it will be noted, are made to extend across the full width of the leaves 23, 24, and moreover to project beyond the outer edge of each leaf, towards the opposite ends of the table. When the 110 halves 19, 20, are brought together, as seen in Fig. 1, the said runners then abut against opposed parts of the aprons 21, and by preventing the leaves from moving too far outward operate to keep them within easy 115 reach.

The several runners 37 are arranged to slide partly over the opposite faces of the pairs of bars 31, 32, and partly over plates 40, secured to the outer ends of the said bars. 120 Preferably and as shown, these ends of the bars are cut into or recessed laterally to receive the plates, so that the contacting faces of the runners will glide smoothly through their entire course. This arrangement is 125 best seen in the plans, Figs. 1, 4 and 8.

A sliding connection is provided between the said runners 37 and the said plates 40, the same including a pin 42, projecting from the inner side of each runner and fitted so 130

as to slide in either one of two horizontal grooves 43 and 44, cut lengthwise through each plate. The grooves are superposed in the width of the plate and situated partly 5 in advance one of the other. They are interconnected by a short vertical passage 45, and further have an open terminal 46, at the plate's upper edge,—all as illustrated in Figs. 4, 6, 7 and 9.

10 It will be observed, with especial reference to the views last above named, that from the moment the principal portions 19 and 20 of the table have been pulled apart, it is a simple matter to draw out the auxiliary leaves 23 and 24 into the opening to be filled intermediately of the said portions. First, the leaves are kept in their depressed positions by the overlying parts 19, 20, and through engagement of the pins 20 42 of their runners 37 with the lower grooves 43 of the plates 40. But, when the pins 42 have reached the passages 45, and are brought into the upper grooves 44, the leaves then attain the level of the parts 19, 25 20, and may be set therebetween. The two leaves may be used in this raised position, or only one of them, in either of the ways represented in Figs. 4, 5, 8 and 9. If a single extension leaf be used, the other leaf 30 will ordinarily be allowed to remain under the corresponding part, 19 or 20, of the table. However, the surplus leaf may be removed, as suggested in Fig. 7, by passing the pins 42 on the runners 37 thereof out 35 through the open terminals 46 of the slotted plates 40. It can then be cleaned or repaired, and afterwards replaced whenever desired. The pins on the runners of either leaf are pushed back into the outer ends of 40 the upper slots 44, on their respective sides of the table, when the several parts of the latter, in its extended form, are driven together subsequently to adjustment.

Supports are provided under the auxiliary leaves 23 and 24, in order to maintain them correctly positioned, after being raised to the level of the main parts 19 and 20 of the table, in the manner hereinabove explained. These supports are located, by preference, 50 centrally of the table, and consist of co-acting blocks, as 49 and 50, respectively secured to the cruciform frame and to the leaves thereover. Two blocks 49 are attached to the frame, and made to extend 55 transversely of the latter, on opposite sides of the pedestal 11. One of these blocks projects under the leaf 23, while the other runs oppositely under the leaf 24. The inner edges of the leaves 23, 24 are likewise 60 equipped with two of the blocks 50, one at the under side of each leaf. As the leaves are being drawn out away from the superimposed table parts 19, 20, their respective blocks 50 are brought to bear upon the 65 blocks 49 of the frame, and the several

blocks co-operate in keeping the leaves raised, up to the level of the said parts 19, 20. In doing this, the blocks further coact with the pins on the runners 37 and the slotted plates 40, in holding the leaves properly elevated. It will be noted that the blocks 49 are of sufficient length to permit the blocks 50 to ride a variable distance thereon, the block 50 of either leaf being advanced farther along the sublying block 49 of the frame if a single leaf is used than when the two leaves are employed. The reason for this will be readily understood by comparing Figs. 4 and 8.

Figures 10 and 11 represent an auxiliary leaf, as 23, provided with a foldable apron 28^a, attached thereto by means of a hinge 51. When the leaf is not in use, the apron is folded up and held under it by a spring catch 52, as shown in Fig. 10. The catch 52 is secured to the under side of the leaf in such a manner that the apron drops into operative position by gravity, as soon as it is released. See Fig. 11. It will be noted that the hinge 51 is located at the inner side 90 of the apron 28^a, and consequently, the latter is enabled to swing far enough outward, when dropped, to fall into alignment with the main apron 21 of the adjoining table section, on either side. It is understood, of course, that both ends of each leaf are fitted with similar aprons 28^a.

The said apron 28^a is urged in its descent, and thereafter stayed in its unfolded position, through the agency of a swinging bracket 53, connected at one edge to the latter-named apron, by a spring-controlled hinge 54. The spring coiled around the hinge tends normally to keep the bracket edgewise relatively to the apron, though the bracket can be oscillated either to right or left. If the latter be forced or pressed away to either side, the apron then can be swung upward together with it, and hooked by the spring catch 52, which will serve to maintain them in closed position. As indicated in both Figs. 10 and 11, the under side of the leaf 23 is formed with a suitable recess to receive the bracket, when it is thus folded with the apron.

The invention in its broader aspects is not limited to the precise construction shown nor to any particular construction by which the invention has been or may be carried into effect, as many changes may be made 120 in the details of the parts without departing from the main principles of the invention and without sacrificing its chief advantages.

I claim:

1. An extension table including, in combination, a centrally disposed vertical support, a frame secured in a horizontal position thereupon, guide-rails extending transversely of said frame by the sides of said 130

support, adjustable sections in slidable engagement with said guide-rails, oppositely slotted aprons depending from said sections, and an auxiliary leaf insertable between the 5 latter from the slots in either one of said aprons.

2. An extension table including, in combination, oppositely located parts adapted to be moved at option toward or away from 10 each other, oppositely slotted aprons respectively depending from said parts, and an auxiliary leaf substantially equal in length to the latter held closely thereto within the slots pertaining to either one of said aprons.

15 3. An extension table including, in combination, a pedestal, a cruciform frame comprising members crossed diagonally on said pedestal at the upper end thereof, guide-rails spanning opposite sides of said frame, adjustable sections overlying said guide-rails, slide bars engaging the latter from the under side of said sections, aprons depending from the sections and provided with slots parallel to said slide bars, and an auxiliary 25 leaf supported by its opposite extremities in said slots.

4. An extension table including, in combination, mated parts adapted to be drawn toward or away from one another, aprons 30 depending therefrom, an auxiliary leaf detachably held substantially in parallelism under either one of said parts within the apron thereof and means arranged to bear from said leaf against said apron.

35 5. An extension table including, in combination, main cover sections adjustable toward or away from each other, oppositely disposed aprons depending therefrom, a movable leaf adapted to be held at the ends 40 by open-ended guideways in either one of said aprons, and a runner for said leaf extending transversely thereof intermediate of its said ends.

45 6. An extension table including, in combination, top sections capable of being held together or set apart at option, adjusting supports for said sections, an auxiliary leaf slidable beneath either one of the sections so as to permit it to be lodged thereunder 50 or retracted for insertion between the sections, guide-plates recessed in opposite sides

of said supports runners on said leaf slidably engaging said plates, and aprons adapted to sustain the leaf by its extremities from the sections while it is moved in either direction. 55

7. An extension table including, in combination, cover sections movable toward or away from each other, adjusting slides therefor, auxiliary leaves detachably held 60 under said sections substantially in position to be slid between the same, supporting blocks under the sections, oppositely disposed aprons depending from the latter, other blocks on said leaves adapted to ride 65 and rest upon said supporting blocks, and guideways in said aprons for concurrently holding the ends of the leaves.

8. An extension table including, in combination, main cover sections adapted to be 70 moved toward or away from each other, aprons respectively depending from said sections, an auxiliary leaf adapted to be interposed between the latter, guideways being provided in said aprons to receive the leaf 75 when not in use, and supplementary aprons on said leaf capable of being placed in alignment with said first-named aprons.

9. An extension table including, in combination, main cover sections adjustable toward or away from each other, slotted aprons depending therefrom, a movable leaf adapted to engage the slots in said aprons and to be positioned intermediate of said sections, and aprons pivotally attached to 85 said leaf so as to be suspended therefrom in alignment with said first-named aprons when the leaf is in its operative position after disengagement from said slots.

10. An extension table including, in combination, main cover sections capable of adjustment to or from each other, an auxiliary leaf insertable therebetween, aprons depending from said sections and having slots to receive the auxiliary leaf when not in use, 90 foldable aprons on said leaf, and automatically acting mechanism serving to place and hold said foldable aprons in alignment with said first-named aprons.

In testimony whereof, I have signed my 100 name to this specification.

MEYER GROSSMAN.
